DISPENSING CARTON FOR LIQUIDS, POWDERS OR THE LIKE

Thomas W. Winstead, Baltimore, Md., assignor to Hedwin Corporation, Baltimore, Md., a corporation of Maryland

Filed Aug. 11, 1959, Ser. No. 57,137

Term of patent 14 years

(Cl. D58—17)

FIG. 1

FIG. 2

FIG. 3

FIG. 4

Figure 1 is a side elevational view of a dispensing carton for liquids, powders or the like, showing my new design with the pouring spout retracted in inoperative position;

Figure 2 is a top plan view thereof;

Figure 3 is a side elevational view thereof with the pouring spout projected and the closure plug removed; and

Figure 4 is an enlarged fragmentary cross-sectional view taken on the line 4—4 of Figure 2, with the closure plug shown in full.

The characteristic features of my design for the dispensing carton disclosed reside in the dispensing spout of

the carton combined with the closure cap thereof having the configurations as shown.

I claim:

The ornamental design for a dispensing carton for liquids, powders or the like, as shown and described.
